UNITED STATES PATENT OFFICE.

JOHN EDWIN KENKEI, OF GREAT FALLS, MONTANA.

DISPENSING MACHINE.

Application filed May 7, 1924. Serial No. 711,632.

This invention relates to a dispensing machine, and has for an object the provision of a simple and efficient improvement on the dispensing machine shown in my Patent No. 1,428,439 issued September 5, 1922, entitled "Dispensing machine."

Another object concerns the provision of a machine in which the feed of the material from a hopper to the delivery device is considerably simplified.

A further object concerns the provision of means whereby the transfer of material from the hopper to the delivery device is prevented until predetermined periods in the operation of the device.

A still further object concerns the provision of means whereby the operating parts are simplified in their construction so that the cost of manufacture is considerably reduced.

Another object concerns the provision of means whereby the delivery of an article to the position of delivery is rendered more certain, so that an article is delivered every time the device is operated.

The invention is illustrated in the drawings, of which

Figure 1 is a side elevation of the device; Fig. 2 is a horizontal section taken on the line 2--2 of Fig. 1;

Fig. 3 is a perspective view of the article delivery device;

Fig. 4 is a section on the line 4--4 of Fig. 2 showing the parts in the position in which an article has been delivered;

Fig. 5 is a similar section showing the parts in the position in which the delivery trough is being filled and an article has been disposed ready to be delivered;

Fig. 6 is a detail section showing the article in the position it assumes as it is about to travel down the delivery chute;

Fig. 7 is a section taken on the line 7--7 of Fig. 4; and

Fig. 8 is a section taken on the line 8--8 of Fig. 4.

The form of the invention shown in the drawings is a preferred form, although it is understood that modifications in the construction and arrangement of the parts and in the character of the materials used may be adopted without departing from the spirit of the invention as set forth in the appended claims.

The device in general includes a single

pivoted member which, at its rear end within the casing of the dispensing device, is formed as a material receiving trough or reservoir divided into compartments, one compartment adapted to receive material from a material hopper and the other compartment adapted to contain material, and from which latter compartment the material is delivered to a delivery position so that it can be transferred by the movement of the pivoted member to a chute, forming part of said member, down which chute it travels to a position where it can be grasped by the person operating the device. In further particulars the improvement relates to a simplified form of operating device which can be made much more economically and, preferably, of a minimum number of parts, so that economy of manufacture is insured and the complexity of the device is reduced.

In the operation of the member a constant barrier is disposed between a main hopper and the material trough, so that no material can get out of the hopper into the casing of the device and can only get into the trough formed on the pivoted member when such member is in a predetermined position. This structural idea is for the purpose of positively controlling the delivery of articles to be dispensed from the hopper to the trough and to regulate the periods during which such delivery takes place.

The device further contemplates the operation of the pivoted member merely by the seizure of the article exhibited in the hand of the operator and in a natural manner withdrawing it from the device. During this withdrawal the pivoted member is moved in such a manner that a new article is moved to the delivery position and more material is fed to the trough or reservoir. Upon the release of the pivoted member from the hand of the operator, gravity restores the member to normal position, and in restoring it to normal position a new article slides down the chute and the reservoir or trough is cut off from the main hopper to stop any further transmission of material from the hopper to the trough.

As shown in the drawings, which illustrate the preferred form of the invention, I provide a casing 1 in which plates 2 and 3 are disposed, these plates forming a hopper to receive articles such as toothpicks 4.

These plates are spaced apart at their inner ends. This space forms an opening through which material would ordinarily pass from the hopper.

5 Adjacent this open space or discharge opening of the hopper I dispose a pivoted delivery member, preferably pivoted in the casing as at 5 on suitable pins. This delivery member is formed, preferably, of sheet material, and at its rear end is provided with a trough 6. This trough 6 is formed by bending the material of the delivery member to form a rear wall 7 and a front wall 8. This trough 6 is divided into 10 two compartments by the dependence into the trough of an intermediate middle wall 9 formed of sheet material. The upper edge of the rear wall 7 is disposed at a certain level above the bottom of the trough 6, and the upper edge 10 of the intermediate wall 9 is disposed at a much higher level than the upper edge of the wall 7. The lower edge 11 of the intermediate wall 9 is disposed a slight distance from the bottom of 15 the trough 6 and this space forms a communicating passage between the two compartments of the trough. The rear compartment in the trough acts as a reservoir for articles such as toothpicks. The front 20 compartment acts as a similar reservoir and opens into a forward portion of the delivery member. This forward portion is in the form of spaced plates 12 and 13 having side plates 14 and 15 to form an enclosed chute 25 down which the toothpicks may travel in a manner similar to that referred to in the above-mentioned patent.

The wall 9 is supported in position by a curved plate 16, preferably integrally connected to the pivoted member.

40 The walls 7 and 9 are preferably curved, their center of curvature being the pivoted axis of the operating member. The wall 7 is provided on its rear surface with ribs 45 such as 17 which run in slots such as 18 formed on the plate 2 to prevent the lateral movement of the wall. It will be noticed that the plate 3 is curved in the same manner as the wall 9 and in the movement of the delivery member these walls lie adjacent each other.

Assuming that a toothpick has traveled 50 down the chute and is resting on vertical plates 19 and 20, by gripping the toothpick and pulling it forwardly the pivoted member will be moved upwardly to the full-line position shown in Fig. 5. This will lower the rear wall 7 of the trough until its upper edge is flush with the surface of the 55 plate 2 whereupon toothpicks will drop into the rear compartment. At the same time, however, it is noticed that the intermediate wall 9 is acting as a barrier to close off the hopper from the other part of the casing. 60 Release of the pivoted member after the 85

toothpick has been withdrawn therefrom causes gravity to return the pivoted member to full line position as shown in Fig. 4.

In the position shown in Fig. 5 it will be noticed that the upper end 21 of an arm 22 is projected through a slot 23 in the bottom of the trough to start forward the toothpicks therein so as to prevent their jamming in the trough. It is also to be noticed that in the position shown in Fig. 5 a toothpick is supported in the manner previously described in my above-mentioned patent, in notches in a pair of plates such as 23 and 24, and that upon the resumption of the normal position of the pivoted member this toothpick will be delivered into the position shown in Fig. 6 so that it can move down the chute to rest on the plates 19 and 20.

It will also be noted that I have provided a stop post 25 which contacts with the under surface of the trough 6, as shown in Fig. 5, when the trough has reached its ultimate position shown therein.

In the operation of the device, when the pivoted member is moved to the position 90 shown in Fig. 5 toothpicks will fall into the rear compartment of the trough, and as the pivoted member drops back to normal position these toothpicks will pass through the front compartment. As this normal position is being assumed, a toothpick will be transferred to the chute and pass down the chute. When the device is operated again from the normal position to the position shown in Fig. 5, a new toothpick is left 95 supported in the notches on the plates 23 and 24 to be subsequently delivered to the chute. Calling the position shown in Fig. 4 the normal position, and the one shown in Fig. 5 the abnormal position, it will be seen 100 that in the abnormal position delivery of toothpicks to the hopper is effected, and in the normal position delivery of a toothpick to the chute is effected. It will be observed that at all times, however, the hopper can 105 only be put into communication with the trough and with it only in the abnormal position of the pivoted member.

The simplicity of the construction of the pivoted member enables it to act efficiently 110 at all times, to be very little likely to get out of order, and to be a construction which can be economically manufactured. It will be observed that by supporting the barrier plate 9 from the curved plate 16 this curved 115 plate 16 acts as a sort of cover for the front compartment of the trough and results in a closed passageway leading from said front compartment to the chute.

120 What I claim is:—

1. An article dispensing device, which 125 comprises a casing, a delivery member pivoted thereto, said pivoted member having a trough formed on its rear end, said trough having a rear wall, and an inter- 130

mediate wall dividing the trough into front and rear compartments, the height of the intermediate wall being considerably in excess of the height of the rear wall.

5. 2. An article dispensing device, which comprises a casing, a delivery member pivoted thereto, said pivoted member having a trough formed on its rear end, said trough having a rear wall, and an intermediate wall dividing the trough into front and rear compartments, the height of the intermediate wall being considerably in excess of the height of the rear wall, the bottom of the intermediate wall being spaced 10 from the bottom of the trough to provide a passage between the two compartments of the trough.

3. An article dispensing device, which comprises a casing, a delivery member pivoted thereto, said pivoted member having a trough formed on its rear end, said trough having a rear wall, an intermediate wall dividing the trough into front and rear compartments, the height of the intermediate wall being considerably in excess of the height of the rear wall, the bottom of the intermediate wall being spaced 15 from the bottom of the trough to provide a passage between the two compartments of the trough, and a chute connected with the front compartment of the trough.

4. An article dispensing device, which comprises a casing, a delivery member

pivoted thereto, said pivoted member having a trough formed on its rear end, said trough having a rear wall, an intermediate wall dividing the trough into front and rear compartments, the height of the intermediate wall being considerably in excess of the height of the rear wall, the bottom of the intermediate wall being spaced 20 from the bottom of the trough to provide a passage between the two compartments of the trough, a chute connected with the front compartment of the trough, and a cover plate connected to the chute extending over the front compartment, said cover plate supporting the intermediate wall.

5. An article dispensing device, which comprises a casing, a hopper having a discharge opening, a pivoted delivery member supported in the casing and having a trough on its rear end and a chute on its front end, said chute connected to said trough, a rear wall on the trough lying adjacent one edge 50 of the discharge opening of the hopper, and an intermediate wall on the trough lying adjacent another edge of the discharge opening of said hopper, said pivoted member adapted to be moved to put the hopper in 55 communication with the trough, said intermediate wall and said rear wall adapted in any position of the pivoted member to prevent escape of material from the hopper except into said trough.

JOHN EDWIN KENKEL.
